UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,266,586.

Specification of Letters Patent. Patented May 21, 1918.

Application filed March 4, 1916. Serial No. 82,176.

To all whom it may concern:

Be it known that I, ARTHUR J. HALL, a subject of the King of Great Britain, and a resident of Wilkinsburg, in the county of Allegheny and State of Pennsylvania, have invented a new and useful Improvement in Systems of Control, of which the following is a specification.

My invention relates to systems of control for dynamo-electric machines and especially to systems that are adapted to control the operation of electric locomotives or other electrically-propelled vehicles.

One of the objects of my invention is to provide a control system of the multiple-unit type for governing the operation of the driving motors of an electric locomotive that comprises two driving units, each of which may comprise one or more motors that are disposed upon the locomotive trucks.

Another object of my invention is to provide a relatively simple system of the above-indicated type embodying means for arranging the motor-circuit connections for different ranges of operating speeds, and also means for effecting initial or starting operation of certain of the driving motors prior to the remaining motors.

During the operation of certain relatively heavy-capacity locomotives of the type under consideration, considerable trouble has been experienced, when hauling trains of relatively light weight or when switching around a train yard, in smashing knuckle-pins or other portions of the train coupling and in "breaking trains in two" when starting, by reason of the fact that too much tractive effort is developed on the first notch of the motor controller, whereby all of the motors are connected in circuit, as is customary. Moreover, when liquid rheostats have been employed in connection with the motor acceleration, such undesirable results have been of greater severity, since, when the liquid is at a low level in the rheostat tanks, the density of the solution is naturally greater and a relatively heavy current surge occurs as a consequence. On the other hand, if the liquid density is reduced to provide the correct value of starting current when the minimum amount of liquid is in the rheostat tanks, an excessive surge of current is produced at the end of the accelerat-

ing period when the rheostat short-circuiting switches are closed.

According to my present invention, I provide means for overcoming the above-mentioned difficulties which comprises a special arrangement of the auxiliary governing circuit connections and a peculiar configuration of the contact segments of a governing controller whereby only a certain portion such, for example, as one-half, of the driving motors or driving units are initially employed, and, consequently, only substantially one-half, or some other predetermined portion, of the total available mechanical energy or draw-bar pull is initially utilized. It follows, therefore, that the objectionable features just recited are completely obviated.

In the accompanying drawings, Figure 1 is a view, in side elevation, of an electric locomotive comprising two driving units for the control of which my invention is adapted; Fig. 2 is a diagrammatic view of the complete main-circuit connections and main control apparatus to be disposed upon the locomotive as shown in Fig. 1; Fig. 3 and Fig. 4 are diagrammatic views showing the arrangement of motor-circuit connections for providing the desired ranges of operating speeds of the motors; and Fig. 5 is a diagrammatic view of the auxiliary governing circuits for manipulating the various pieces of main-circuit control apparatus that are shown in Fig. 2.

Referring to the drawings, the system shown is adapted for the control of one or more locomotives 1, the trucks 2 and 3 which are respectively provided with driving motors or sets of motors M1 and M2. Obviously, the arrangement of motors with respect to the vehicle is relatively unimportant and my invention is equally applicable to locomotives comprising two half units of the illustrated type or to any other desired arrangement of driving truck units or driving motors.

In Fig. 2, the system illustrated comprises a plurality of supply-circuit conductors 4, 5 and 6 which are adapted to deliver poly-phase alternating-current energy to the poly-phase induction driving motors M1 and M2; a plurality of sets of line switches A1, B1 and C1, and A2, B2 and C2 for respectively connecting the supply-circuit conductors 4, 5 and 6 to the motors M1 and M2; a pair of

5 pole-change-over switches PCO#1 and PCO#2 for arranging the winding connections of the motors M1 and M2 for different numbers of poles; a plurality of liquid rheostats LR1 and LR2 that are respectively adapted to be connected in the secondary circuits of the motors M1 and M2 for governing the acceleration thereof; a plurality of operating mechanisms OM1 and OM2 for 10 respectively actuating the rheostats LR1 and LR2; and a plurality of sets of switches X1 and Y1, and X2 and Y2 for respectively establishing short-circuit connections for the rheostats LR1 and LR2.

15 The motors M1 and M2 are preferably of the wound-rotor polyphase induction type and have suitable primary windings P1 and P2 and secondary windings S1 and S2, respectively. Initially, the windings are connected in delta relation and are adapted for a predetermined number of poles, for instance, 8 poles, while the windings may be connected in such manner as to halve the number of poles and thus produce machines of the four-pole type. No detailed description of the means for adapting the motors for different numbers of poles will be given, inasmuch as such connections are old and well-known in the art.

20 30 The pole-change-over switch PCO#1 comprises a group 7 of coöperating stationary and movable main contact members and a group 8 of coöperating stationary and movable interlocking or auxiliary contact members that are adapted to make coöperative engagement upon the position-indicating lines 8P and 4P. The pole change-over switch PCO#2 similarly comprises a group of main contact members and a group 35 40 10 of auxiliary interlocking contact members that are also adapted for coöperative engagement on the corresponding position-indicating lines 8P and 4P. When the pole-change-over switches occupy their 8P positions, the windings of motors M1 and M2 are arranged for 8 poles while in the 4P position, the change-over switches adapt the motor windings for 4 poles. A plurality of suitable electro-magnetic actuating devices 45 50 11 and 12 are preferably associated with the respective change-over switches.

55 By proper manipulation of the switches PCO#1 and PCO#2, the motors M1 and M2 may be initially connected in parallel relation, with 8 poles, as shown in Fig. 3, and, subsequently, in parallel relation, with 4 poles, as illustrated in Fig. 4, whereby the motors are adapted for two different ranges of operating speeds, for instance, 60 from zero to 14 M.P.H. and from 14 to 28 M.P.H.

65 The liquid rheostats LR1 and LR2 may be of any suitable construction and, in general, severally comprise an electrolyte-containing tank or vessel 13; a plurality of

suitably-spaced plates or electrodes 14 that are adapted to be connected to the secondary induction motor windings through the pole-change-over switches; and a combined discharge and regulating valve 15 which is 70 adapted to regulate the height of the electrolyte in the tank 13, in accordance with a familiar practice. It will be understood that the particular type of liquid rheostat that is employed is immaterial to my present invention and no further description thereof is believed to be necessary here, although, for a more complete exposition of the structure and operation of the preferred type of rheostats, reference may be 75 had to my co-pending application, Serial No. 873,919, filed November 25, 1914.

80 The operating mechanisms OM1 and OM2 for the valves 15 are of a well-known type and are shown as comprising a suitable fixed pulley-wheel 20 around which is wound a rope or cable 21, one end of which is suitably associated with a rod 22 that is secured to the valve 15, and a suitable counterbalancing weight 23 is attached to the 85 free end of the cable 21. The shaft of the pulley wheel 20 is provided with a pinion member 24 which engages a horizontally-movable rack member 25, with the opposite ends of which a pair of pistons 26 and 27 are respectively associated to operate within suitable cylinders 28 and 29. A pair of valves 30 and 31 are respectively associated with the cylinders 28 and 29 and are adapted to admit fluid-pressure to the cylinders 90 through a plurality of pipes or passages 32 and 33, respectively, from any suitable source of fluid pressure (not shown), under conditions to be set forth. The valves 30 and 31 are respectively provided with actuating coils On—1 and Off—1. The valve 30 is normally closed to exclude fluid pressure from the cylinder 28 and to connect the cylinder to the atmosphere, whereas, the other valve 31 is normally open to admit fluid-pressure to the cylinder 29 and to interrupt the communication of the cylinder with the atmosphere, whereby the operating mechanism and the valve 15 are normally biased to the respective positions shown. 100

105 The rheostat LR1 is provided with an auxiliary or interlocking contact member LR1—up that becomes operative only when the rheostat is completely filled, and with a second contact member LR1—X that is operative except when the rheostat occupies its "flush-level" or substantially discharged position, for purposes to be set forth. The contact member LR1—X is shown for illustrative purposes only, and the preferred 110 structure embodies an oscillatable drum that is actuated by stops on the valve rod, as fully described in my co-pending application, Serial No. 876,484, filed December 10, 1914. The other rheostat LR2 is simi- 115 120 125 130

larly provided with auxiliary contact members.

To operate the mechanism OM1, the two actuating coils On-1 and Off-1 are simultaneously energized as set forth in detail in connection with Fig. 5, whereupon fluid-pressure is admitted to the cylinder 28 and is released from the cylinder 29, thereby effecting a movement of the pistons 26 and 27 toward the right, as shown in the drawing, and, consequently, manipulating valve 15 to admit electrolyte to the tank 18. To arrest movement of the operating mechanism at any desired time, the coil Off-1 is deenergized, whereby balanced fluid-pressure conditions obtain in the two cylinders and the desired stoppage is immediately effected. To return the mechanism to the normal position, it is merely necessary to de-energize both actuating coils, whereupon fluid-pressure conditions revert to the original state and the mechanism is actuated to the illustrated position. It will be understood without further description that the operating mechanism OM2 is similar in all respects to the operating mechanism OM1, being provided with actuating coils respectively marked On-2 and Off-2.

Reference may now be had to Fig. 5 wherein the auxiliary governing circuits shown comprise a master controller MC having three independently-movable drums; viz., a speed drum SD, an accelerating drum AD, and a reversing drum RD. The speed drum is adapted to successively assume an off position, a preliminary position α , an initial running position A which corresponds to the completed main-circuit connections that are illustrated in Fig. 3, a transition position β , and a final running position B that corresponds to the completed motor-circuit connection shown in Fig. 4. The accelerating drum AD is adapted to successively assume an off position and three positions respectively marked "Lower," "Hold," and "Raise," for suitably governing the operation of the mechanisms OM1 and OM2 of the several liquid rheostats.

In order to provide for multiple-unit train-operation, a plurality of train-line conductors TL are employed, in accordance with a familiar practice, and serve as intermediate conductors between the master controller drums, a suitable battery B and the various actuating coils of the switching devices that are illustrated in Fig. 2. In addition, a plurality of interlocking contact members that are either included in the groups 8 and 10 of the pole-change-over switches or are associated with the line switches or the operating mechanisms as shown in Fig. 2, are employed as about to be described in detail. It will be observed that the reversing drum RD forms a part

of the master controller and that the usual actuating coils r' and f' of a familiar main-circuit reversing-switch RS are illustrated, although, for the sake of simplicity and clearness, the main-circuit reversing-switch RS is omitted from Fig. 2. However, such a reversing switch is normally employed in connection with the operation of my system, as will be understood.

Assuming that the main and auxiliary circuit connections are as illustrated, the operation of the system may be set forth as follows: The speed drum SD is moved to its initial or preliminary position α , while the accelerating drum AD may be moved to its final operating position "Raise," whereby one circuit is completed from the positive terminal of the control battery B through conductor 40, train-line conductor 41, conductors 42 and 64, control fingers 65 and 66, which are bridged by contact segment 67 of the accelerating drum AD in its position "Raise," conductor 68, train-line conductor 69, conductor 70, the actuating coil On-1, conductors 71 and 72, contact member PCO#1-8P, conductors 73 and 74, train-line conductor 75, conductor 76, control fingers 77 and 78, which are bridged by contact segment 79 of the speed drum SD, conductor 80, train-line conductor 62 and conductor 63 to the negative battery terminal.

A simultaneous circuit is established from the contact segment 67 of the accelerating drum AD through control finger 81, conductor 82, train-line conductor 83, conductor 84, and the actuating coil Off-1, whence circuit is completed through conductor 71 as just traced.

A further circuit is thereupon established from the positively-connected connector 42 through control fingers 43 and 44 which are bridged by contact segment 45 of the speed drum, conductor 46, train-line conductor 47 and conductors 48 and 49 where the circuit divides, one branch including interlock LR1-X and the parallel-connected actuating coils of the switches A1, B1, and C1, and the other branch, under subsequent conditions, including conductor 49a, interlock LR2-X (not included in circuit at present) and the parallel-connected actuating coils of the switches A2, B2 and C2, and a common circuit being completed through conductors 50 and 51, contact member 52 of the main-circuit reversing-switch RS, conductor 53, train-line conductor 54, conductor 55, contact member 56 of the reverse drum RD in its forward position, conductor 57, control fingers 58 and 59, which are bridged by contact segment 60 of the speed-drum, and conductor 61 to the negative train-line conductor 62.

Upon the closure of the valves 30 and 31 of the operating mechanism OM1 and the closure of the line switches A1, B1 and C1,

the motor M1 is gradually started into operation to effect the initial acceleration of the locomotive.

Upon movement of the speed drum to the initial running position A, another circuit is completed from the negatively-energized contact segment 79 of the drum through control finger 85, conductor 86, train-line conductor 87, conductors 88 and 89, interlock PCO#2—8P, conductors 90 and 91 and the parallel-related actuating coils On—2 and Off—2 which are respectively connected through conductors 92 and 93 to the train-line conductors 69 and 83 and thence to the control fingers 66 and 81 of the accelerating drum.

Consequently, dependent upon the will of the operator, sometime after the motor M1 is connected into circuit to effect initial acceleration of the train, the other motor M2 is brought into operation and thus full tractive effort is available a certain time after starting to accelerate the train to the speed that corresponds to running position A of the speed drum.

When the liquid in the rheostats LR1 and LR2 has reached its upper level, a circuit is established from the contact segment 67 of the accelerating drum through control finger 94, conductor 95, train-line conductor 96, conductors 97 and 98, the parallel-related actuating coils of the short-circuiting switches X1 and Y1, conductor 99, interlock LR1—up, and thence through conductors 100 and 72 to the negative battery terminal, as hereinbefore set forth. The short-circuiting switches of the liquid rheostat LR1 are thus closed, and a similar closure of the switches X2 and Y2, occurs by reason of the completion of a circuit from conductor 97 through the parallel-connected actuating coils of the switches X2 and Y2, conductor 101 and interlock LR2—up to the negatively-connected conductor 90.

To effect further operation of the system by transition of the motor-winding connections to the 4-pole arrangement that is illustrated in Fig. 4, the speed drum SD may be next actuated to its intermediate or transition position b, whereupon, at first, contact segment 79 is disengaged from contact finger 77, thereby deenergizing the circuits of the actuating coils of the short-circuiting switches X1, Y1 and also the actuating coils On—1 and Off—1 of the operating mechanism OM1, thus effecting the return movement of the operating mechanism, which, in turn, effects the deenergization of the actuating coils of the primary switches A1, B1 and C1 by reason of the exclusion from the governing circuits of the last-mentioned switches of the interlock LR1—X.

When the speed drum SD reaches its transition position b, a circuit is established

from the contact segment 79 through control finger 110, conductor 111, train-line conductor 112, conductors 113 and 114, interlock B1—out, conductor 115, the actuating coil 4P of the pole-change-over switch PCO#1, interlock 116 thereof in the position 8P, and thence through conductor 97 to the positive terminal of the battery B in accordance with a circuit that has already been traced.

The pole-change-over switch PCO#1 is thus actuated to its 4P position to correspondingly re-arrange the motor winding connections, and a governing circuit is thereupon completed from the conductor 113 through contact member PCO#1—4P, conductor 71, and the actuating coils On—1 and Off—1 of the operating mechanism OM1, provided that the accelerating drum AD occupies its position "Raise" to complete the energizing circuits that have previously been described.

When the transition of connections of the motor M1 has been effected, the speed drum SD may be actuated to its final position B, whereupon at first the contact segment 79 becomes disengaged from the control finger 85 and as a result, the coils of the short-circuiting switches X2 and Y2 and the actuating coils On—2 and Off—2 of the operating mechanism OM2 are deenergized to permit a return movement of the liquid rheostat LR2 to its discharge position. The return of the rheostat to such position effects an interruption of the circuit of the actuating coils of the switches A2, B2 and C2 by breaking the connection of the conductor 49^a with the actuating coils by reason of the exclusion of the interlock LR2—X.

When the speed drum SD reaches its final position B, a circuit is completed from the contact segment 79 through control finger 116, conductor 117, train-line conductor 118, conductors 119 and 120, interlock B2—out, conductor 121, the actuating coil 4P of the pole change-over switch PCO#2, contact member 122 thereof in the position 8P, and thence through conductor 97 as previously set forth. The other motor M2 is thus changed over to the 4-pole arrangement. The above-described successive transition of the motors from one set of connections that corresponds to a certain speed to another set of connections that corresponds to a higher speed forms no part of my present invention and is fully shown and described and claimed in my co-pending application, Serial No. 861,767, filed September 15, 1914.

It will be understood, without further extended description, that, upon the energization of the actuating coils Off—1 and Off—2, the corresponding interlock members LR1—X and LR2—X again respectively

complete the circuits of the primary switches A1, B1 and C1, and A2, B2 and C2, the level of the electrolyte in the respective liquid rheostats is gradually raised in accordance with the operation of the mechanisms OM1 and OM2, and the various short-circuiting switches are again closed as soon as the liquid rheostats occupy their completely-filled position.

- 10 To further control the operation of the liquid rheostats during acceleration of the motors, the accelerating drum may be moved to its intermediate position "Hold," thereby deenergizing the coils Off-1 and Off-2 and thus arresting the movement of the operating mechanisms OM1 and OM2, as previously described; and the electrolyte levels may be lowered at any time by moving the drum AD to its position "Lower" 20 to thus deenergize both the "Off" and the "On" actuating coils, as is familiar practice.

It will be observed that I have thus provided a relatively simple and reliable control system for initially effecting the accelerating operation of a predetermined portion of a number of driving units in an electric vehicle prior to the accelerating operation of the remaining driving units, whereby 30 the previously mentioned-undesirable operating results are entirely obviated.

Obviously, various modifications of the herein-described motor winding connections and auxiliary governing circuits may be effected without departing from the spirit and scope of my invention and I desire, therefore, that only such limitations shall be imposed as are indicated in the appended claims.

40 I claim as my invention:

1. In a system of control, the combination with a supply circuit, a plurality of driving motors adapted to receive energy therefrom, and means for arranging the connections of said motors for different concurrent ranges of operating speeds, of means for initially effecting operation of certain of said motors prior to the remaining motors.

2. In a system of control, the combination with a supply circuit, a plurality of driving motors adapted to receive energy therefrom, and means for arranging the connections of said motors for different concurrent ranges of operating speeds, of means for successively connecting said motors in circuit during the initial accelerating period, whereby only a portion of the motors initially produce mechanical energy.

3. In a system of control, the combination with a supply circuit, a plurality of driving motors adapted to receive energy therefrom, and means for arranging the connections of said motors for different concurrent ranges of operating speeds, of means for initially employing one-half of the motors prior to

the remaining half thereof, whereby substantially only one-half of the available driving energy is initially utilized.

4. In a system of control, the combination with a supply circuit, a plurality of polyphase induction motors adapted to drive a common load and to receive energy from said supply circuit, and switching means for arranging the connections of said motors for different concurrent ranges of operating speeds, of means for effecting successive initial operation of said motors.

5. In a system of control, the combination with a supply circuit, a plurality of polyphase induction motors adapted to drive a common load and to receive energy from said supply-circuit, and switching means for arranging the connections of said motors for concurrent operation with different numbers of poles, of means for effecting successive initial operation of said motors.

6. In a system of control, the combination with a supply circuit, a plurality of polyphase induction motors adapted to drive a common load and to receive energy from said supply circuit, and switching means for arranging the connections of said motors for different concurrent ranges of operating speeds, of controllable electrically-governed means for controlling the operation of said switching means and for causing the switching means of one motor to effect initial accelerating operation thereof prior to the operation of the other motor.

7. In a system of control, the combination with a supply circuit, a plurality of polyphase induction motors adapted to drive a common load and to receive energy from said supply circuit, and switching means for arranging the connections of said motors for different concurrent ranges of operating speeds, of electrical means for controlling the operation of said switching means and comprising a master controller adapted to occupy a plurality of operating positions and to initially effect successive accelerating operation of said motors.

8. In a system of control, the combination with a supply circuit, a plurality of polyphase induction motors adapted to drive a common load and to receive energy from said supply circuit, and switching means for arranging the connections of said motor for different concurrent ranges of operating speeds, of electrical means for controlling the operation of said means and comprising a master controller adapted to occupy a plurality of operating positions and having a plurality of conducting segments for respectively governing the operation of said motors, said segments being arranged to effect the successive initial accelerating operation of the motors.

9. In a system of control for an electric vehicle having a pair of driving units, the

combination with a motor for each unit, and means for arranging the motor connections for different concurrent ranges of operating speeds, of means for effecting initial driving 5 operation of one unit prior to that of the other unit.

10. In a system of control for an electric vehicle having a pair of driving units, the combination with a polyphase induction motor for each unit, and means for changing the number of poles of said motors to obtain a plurality of concurrent ranges of operating speeds, of means for effecting successive initial accelerating operation of said units, 15 whereby substantially only one-half of the available driving energy is initially utilized.

11. In a system of control for an electric vehicle having a pair of driving units, the combination with a driving motor for each 20 unit, separate means associated with each motor for changing the motor connections for different concurrent ranges of operating speeds, and separate means associated with each motor for governing the acceleration 25 thereof for each range of speed, of remote-

control means for effecting successive initial operation of said motors and for effecting concurrent operation of both of said acceleration-governing means.

12. In a system of control for an electric 30 vehicle having a pair of driving units, the combination with a driving motor for each unit, separate means associated with each motor for changing the motor connections for different ranges of operating speeds, and 35 separate means associated with each motor for governing the acceleration thereof for each range of speed, of electrical remote-control means for governing the speed-changing means and the acceleration-governing means for each motor and embodying a controller for effecting concurrent operation of both of said acceleration-governing means, and a second controller for effecting successive initial accelerating operation of said 40 motors.

In testimony whereof, I have hereunto subscribed my name this 29th day of Feb., 1916.

ARTHUR J. HALL.
